UNITED STATES PATENT OFFICE.

JAMES O. HUTCHINSON, OF EVANSVILLE, WISCONSIN.

BUCKLE.

SPECIFICATION forming part of Letters Patent No. 242,131, dated May 31, 1881.

Application filed February 23, 1881. (No model.)

To all whom it may concern:

Be it known that I, JAMES O. HUTCHINSON, a citizen of the United States, resident at Evansville, in the county of Rock and State of Wisconsin, have invented certain new and useful Improvements in Buckles; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 is a vertical longitudinal sectional view of a buckle embodying my improvements, and Fig. 2 is a plan view of the same. Fig. 3 is a side elevation of the buckle with the strap C removed, showing the curve of the parts.

This invention has relation to two-part buckles; and it consists of a concavo-convex frame having a rear cross-bar, a front cross-bar provided with a rigid depending tongue and side loops for attaching straps, and a second interlocking frame having front, rear, and intermediate cross-bars, and notches or recesses in the side bars near the rear cross-bar to receive the side bars of the other frame, and permit the projecting ends of the cross-bar of the interlocking frame to ride upon the curved side bars of the main or stationary frame, as will be hereinafter more fully described, and particularly pointed out in the claim.

Referring by letter to the accompanying drawings, A designates the main or fixed frame of the two-part buckle (secured to the stationary strap, as shown in Fig. 1) having the rear cross-bar, a, the front cross-bar, a³, the downwardly-curved side bars, a' a', the side loops, z z, and the depending rigid tongue a⁴. The side bars of the main frame are sharply curved, as shown in Fig. 3, so that the bearing-surfaces of the recesses b⁵ of the interlocking frame B will have a double-cam action upon the main frame in manipulating the buckle to shorten or lengthen the straps.

B designates the interlocking or removable

frame of the two-part buckle, having the rear cross-bar, b⁶, provided with ends b⁷ b⁷ projecting beyond the notches or recesses b⁵ b⁵ made in the outer edges of the side bars, b⁴ b⁴, of this latter frame. The side bars, b⁴ b⁴, of the frame B are curved, as shown in Fig. 1, and are connected near the middle by a cross-bar, b³, and at the front by a flat cross-bar, b.

The stationary strap is connected to the rear cross-bar, a, of the frame A, and is provided with the usual box-loop, D.

The strap C is perforated at intervals to receive the tongue a⁴, and is introduced beneath the cross-bar b of the frame B, over the cross-bar b³, under the cross-bar a³ of the frame A, over cross-bar b⁶ of frame B, and then to the loop D.

Strain upon the straps will cause the tongue a⁴ to enter the perforations in the strap C when exerted in the proper direction, and a reverse strain or pull will release the tongue when it becomes necessary to shorten or lengthen them.

The strain upon the straps causes the buckle to clamp the strap C tightly at four points—viz., 70 against the bar b, the bar b³, the tongue a⁴, and between the bars a³ and b⁶—so that if any one of these portions were to be accidentally broken the strap C would still be held by the buckle.

What I claim is—

In a two-part buckle, the frame A, having the downwardly and sharply curved side bars, a' a', and the cross-bars a and a³, the latter having the rigid depending tongue a⁴, in combination with 80 the interlocking frame B, having recessed side bars, b⁴ b⁴ b⁵ b⁵, curved, as shown, and provided with the cross-bars b, b³, and b⁶, the latter having the projecting ends b⁷ b⁷, substantially as and for the purposes set forth.

In testimony whereof I affix my signature in presence of two witnesses.

JAMES O. HUTCHINSON.
